(57) CLAIM

The ornamental design for a combined toothpaste, toothbrush holder and timer, as shown and described.

DESCRIPTION

FIG. 1: is a top, front, and right side perspective view of a combined toothpaste, toothbrush holder and timer, showing my new design;

FIG. 2: is a top view thereof;

FIG. 3: is a bottom view thereof;

FIG. 4: is a side elevational view, the opposite side being a mirror image thereof;

FIG. 5: is a front elevational view thereof;

FIG. 6: is a rear elevational view thereof; and,

FIG. 7: is a vertical cross sectional view broken-away horizontally.
